UNITED STATES PATENT OFFICE

GEORGE L. HATHEWAY, OF NEW YORK, N. Y., ASSIGNOR TO THE RATTAN MFG. CO.,
OF NEW HAVEN, CONNECTICUT, A CORPORATION.

SQUEEZE CONNECTOR.

1,425,382.

Specification of Letters Patent. Patented Aug. 8, 1922.

Application filed October 3, 1921. Serial No. 505,151.

To all whom it may concern:

Be it known that I, GEORGE L. HATHEWAY, a citizen of the United States, residing at New York, in the county of New York and 5 State of New York, have invented a new and useful Improvement in Squeeze Connectors; and I do hereby declare the following, when taken in connection with the accompanying drawings and the characters of reference 10 marked thereon, to be a full, clear, and exact description of the same, and which said drawings constitute part of this application, and represent, in—

Fig. 1 a plan view of a squeeze connector, 15 provided with a reducing device constructed in accordance with my invention.

Fig. 2 a sectional view of the same.

Fig. 3 an enlarged perspective view of the reducing device, detached.

20 This invention relates to an improvement in squeeze connectors such as are commonly employed in connecting electric conductors with outlet boxes. These connectors are made in standard sizes to fit standard boxes, 25 but conductors vary in size, so that frequently a connector is too large for the conductor and another connector must be substituted. The object of this invention is to provide a reducing device adapted to be used 30 between the connector and conductor so that a relatively small conductor may be firmly held by a larger connector and the invention consists in the construction as hereinafter described and particularly recited in the 35 claims.

In carrying out my invention, I employ a reducing device 5, formed from a strip of metal, one end 6 of which is longitudinally bowed, corresponding to the opening 40 through the connector 7 with which it is to be used. The other end 8 is doubled upon

the end 6 to a point adjacent to the center thereof and then turned outward. This outwardly projecting end is formed with a slot 9 through which the usual screw 10, which contracts the connector, may pass. The connector has the usual threaded sleeve 11, on which is a nut 12 by which the connector is mounted in an outlet box 13. This reducing device is inserted between the conductor 14 45 and the connector so that, when the screw 10 is turned inward, the conductor will be firmly gripped.

It is obvious, without further illustration, 50 that the reducing device might be formed from two pieces of metal secured together in any desired manner, such, for instance, as by spot welding. It is also obvious that the end 6, instead of being arranged at substantially a right angle to the end 8, might continue in a curve, so as to line one side of the connector, as indicated by broken lines in Fig. 1.

I claim:

1. A reducing device for squeeze connectors consisting of a longitudinally bowed portion, and a straight portion at an angle to the bowed portion and formed with a clearance slot. 55

2. The combination with a squeeze connector of a reducing device consisting of a strip of metal having one end longitudinally bowed and the other end doubled back and turned outward, said outward extension formed with a clearance slot. 60

In testimony whereof, I have signed this specification in the presence of two subscribing witnesses.

GEORGE L. HATHEWAY.

Witnesses:

P. SIMON,
M. A. THOMS.
